UNITED STATES PATENT OFFICE.

JOHN B. GOODWIN, OF BALTIMORE, MARYLAND, ASSIGNOR TO SOVEREIGN GRAND LODGE OF THE INDEPENDENT ORDER OF ODD FELLOWS, OF BALTIMORE, MARYLAND, A CORPORATION OF MARYLAND.

DESIGN FOR A BADGE.

No. 37,914.

Specification for Design.

Patented March 27, 1906.

Application filed February 7, 1906. Serial No. 300,010. Term of patent 14 years.

To all whom it may concern:

Be it known that I, JOHN B. GOODWIN, a citizen of the United States, residing in the city of Baltimore, State of Maryland, have invented a new, original, and ornamental Design for Badges, of which the following is a specification, reference being had to the accompanying drawing, forming part thereof.

The figure is a front view of a badge, showing my new design.

I claim—
The ornamental design for a badge, as shown.

JOHN B. GOODWIN.
